UNITED STATES PATENT OFFICE.

JAMES JOLLY, OF BOLTON, ENGLAND.

DRAWING OR DRAFTING MECHANISM.

Application filed July 18, 1927. Serial No. 206,694.

This invention relates to the drafting of cotton, wool, silk, artificial silk and other fibres in preparation for spinning and apparatus employed therefor, particularly applicable for spinning mules, spinning frames and like machines, more especially for single rovings direct from the slubbing or roving frame for the production of coarse counts of yarn, though it may also be employed with double rovings for the production of finer counts of yarn.

The invention consists in a process or method of high drafting comprising passing the slub or rove to and fro over a pair of rollers one of which is grooved circumferentially with grooves of varying diameter and in constructing one or more lines of drafting rollers with a series of annular grooves of varying diameter from which the slub or rove is passed to and fro in succession over a second roller either plain or similarly grooved.

The invention will be fully described with reference to the accompanying drawings.

Fig. 1 is a side elevation of roller stand.
Fig. 2 is a plan of drawing rollers.

Figs. 3 and 4 are plans of drawing rollers showing modifications.

Fig. 5 is a perspective view showing the method or process of high drafting.

In carrying out the invention it is proposed to employ two additional lines 4 and 5 of rollers as well as the ordinary lines 1, 2 and 3 of fluted rollers, all mounted in a roller stand S with ordinary weighted rollers A, held in position by cap-bars B.

In the construction shown in Fig. 2 the line 5 of rollers comprises a roller D formed with a number of annular grooves d^1, d^2, d^3, d^4 of different diameters each successive groove being of greater diameter than the preceding one giving a gradual increase in diameter from the groove d^1 to the groove d^4 and the line 4 of rollers comprises a smooth surface or fluted roller E.

In the construction shown in Fig. 3 the line 4 of rollers comprises a roller G formed with a number of annular grooves g^1 to g^4 of different diameters each successive groove being of greater diameter than the preceding one giving a gradual increase in diameter from the groove g^1 to the groove g^4 and the line 5 of rollers comprises a smooth surface or fluted roller H.

In the construction shown in Fig. 4 both lines of rollers 4 and 5 comprise rollers K and M formed with annular grooves K^1 to K^4 and

m^1 to m^4 . On one or both of the rollers K and M the grooves are of different diameters each successive groove being of greater diameter than the preceding one giving a gradual increase in diameter.

This construction of grooved roller gives a greater surface speed to each successive groove as the roller rotates.

The two lines of rollers 4 and 5 are preferably driven at the same speed.

It is preferred to have the grooved roller as line 5 as shown in Fig. 2, though it may be line 4 as in Fig. 3 or both lines 4 and 5 may be grooved as in Fig. 4.

In operation the rove with as little twist as possible is passed from the guide funnel N over the smooth or fluted roller and around the small diameter groove of the grooved roller, again around the smooth or fluted roller and the second groove of the grooved roller and so on around any number of the grooves as required as indicated by diagram Fig. 5. As each successive groove has a larger diameter and greater surface speed than the preceding one, a certain amount of draft is imparted to the rove as it passes from one groove to the next. After passing over two or more of the grooves in the grooved roller the rove passes in the regular way to the lines 3, 2 and 1 of rollers.

What I claim as my invention and desire to protect by Letters Patent is:—

1. The combination with a three-roller draft frame, of two additional lines of rollers added thereto and in such a manner that the material being drafted is passed to and fro, over and around these additional lines of rollers, the rollers in one of the additional lines being provided with grooves of varying diameters.

2. The combination with a three-roller draft frame, of two additional lines of rollers added thereto and in such a manner that the material being drafted is passed to and fro, over and around these additional lines of rollers, the rollers in one of the additional lines being provided with grooves of varying diameters, and each groove being of greater diameter than the preceding groove over which the material has passed.

3. The combination with a three-roller draft frame, of two additional lines of rollers added thereto and in such a manner that the material being drafted is passed to and fro, over and around these additional lines of rollers, the rollers in one of the additional lines of rollers, the rollers in one of the additional

lines being provided with grooves of varying diameters, and a guiding funnel adjacent to the smallest diametered groove to direct material thereto.

5 4. The combination with a three-roller draft frame, of two additional lines of rollers added thereto and in such a manner that the material being drafted is passed to and fro, over and around these additional lines 10 of rollers, the rollers in one of the additional

lines being provided with grooves of varying diameters, each groove being of greater diameter than the preceding groove over which the material has passed, and a guiding funnel adjacent to the smallest diametered groove 15 to direct material thereto.

In testimony whereof I have hereunto set my hand:

JAMES JOLLY.
